Patented Feb. 8, 1927.

UNITED STATES PATENT OFFICE.

ROBERT W. HULL, OF CONNERSVILLE, INDIANA, ASSIGNOR TO REX MANUFACTURING COMPANY, OF CONNERSVILLE, INDIANA, A CORPORATION OF INDIANA.

CONNECTING MEANS FOR TWO-PART AUTOMOBILE DOORS.

Application filed March 29, 1924. Serial No. 702,962.

My said invention relates to improved yielding and flexible connecting means for two-part automobile doors having demountable upper sections such as are commonly used in connection with what are known as 5 winter tops.

Referring to the accompanying drawings, which are made a part hereof and on which similar reference characters indicate similar

10 parts,

Figure 1 is a fragmentary side elevation of a door looking from the inside of the vehicle body.

Figure 2 a section on line 2—2 of Figure 1, and

Figure 3 a section on line 3—3 of Figure 1.

In the drawings reference character 10 indicates the outer panel of the demountable 20 upper door section which section comprises also a wooden frame surrounding the sight opening of the door and supporting one or more panes of glass. At the closing side of the door a strip of sheet metal 12 is attached to the upright member 11 of the wooden frame in the manner illustrated in Figure 3 by means of rivets 13, or in any other suitable or convenient manner. In the present instance it will be seen that the 30 rivets extend through both sides of the bent strip 12 the bar 11 and the panel 10 thereby securing all of the parts firmly together.

At its inner forward corner the bar 11 is cut away to provide a square socket to receive the square upright end of a connecting rod 14, the conformation of the socket thus formed being intended to be the same as a cross section of this part of the rod so that the rod will be held securely in place. The 40 body of said rod extends along the lower side of the lower bar 11' of the wooden frame adjacent the lower edge of the demountable door section. The connector rod is bent in such a manner that the body 14 will diverge from the plane of the door when the upright arm is entered in the 45 socket of the member 11.

A post 15 is slidably mounted on the body of the connector rod near its extremity the post being flattened at its lower end and having a head with an opening matching the shape of the rod. It is to be understood that the rod is preferably square but it may assume other rectangular forms or it may be 55 elliptical or have any other irregular or non-

circular shape if only the shape be such that the post will not turn on the rod. The relation of the post to the rod and the door section is such that it lies in a plane diverging toward the interior of the vehicle body 60 away from the plane of the upper door section and also away from the plane in which the angularly related parts of the connector normally lie. A stirrup 16 is provided in connection with the bar 11' said 65 stirrup embracing the bar and being secured thereto by rivets 17 extending through the bar and both side members of the stirrup although other conventional or preferred means may be used for securing the parts together. The function of this stirrup is to 70 confine the body of the connector bar loosely with relation to the upper door section. A plate 18 extends across the joint between the bars 11 and 11' for bracing the corner 75 of the door.

In positioning the upper demountable door section on the lower permanent door section the connector is placed under stress by bending the horizontal body portion toward the 80 door so that the post 15 may enter a socket in the lower door section or may be otherwise conveniently secured thereto. The effect of this is to impart a tendency to the upper door section to contact with the door frame at its closing side before the hinge side reaches closing position. At the same time the demountable section of the door is tilted to cause the post to enter the socket 85 in the lower door section thereby imparting a tendency for the upper side of the door to strike the door frame before the lower side of the door reaches closing position. By thus biasing the upper and closing sides or 90 edges of the door toward the vehicle body I am enabled to prevent rattling and rumbling noises due to looseness in the connections between the door and the vehicle body. 95

It will be obvious to those skilled in the art that various changes may be made in my device without departing from the spirit of the invention and therefore I do not limit myself to the precise construction shown in the drawings and described in the specification, but only as indicated in the appended 100 claims.

Having fully described my said invention what I claim is:

1. A two-part door for vehicles comprising an upper demountable section adapted 110

- to be positioned on a lower permanent section said upper section having a vertical socket formed therein at the closing side of the door and said socket being rectangular
- 5 in section, a connector rod rectangular in section having an upright arm fitting flush in said socket and a body extending along the lower margin of the demountable section in the same plane with said arm, a depending
- 10 stirrup embracing the body of said rod and a post secured to the body of the connector rod and adapted to enter a socket set slightly inclined from the vertical plane of said connector rod said post normally lying in a plane diverging from said vertical plane whereby when the upper demountable section is in place on the lower permanent section its upper edge and its free vertical edge will be biased toward the vehicle body, substantially as set forth.
- 15 2. A two-part door for vehicles comprising an upper demountable section adapted to be positioned on a lower permanent section said upper section having a vertical
- 20 socket at one side of the door, a connector rod having a normally upright arm in said socket and a body extending along the lower edge of said upper section, and a post having an opening fitting closely about a part of said body non-circular in section said post lying in a plane inclined relatively to that of the upper door section whereby when the post is positioned in the plane of the lower door section the upper edge of the upper door section is biased toward the vehicle body, substantially as set forth.
3. A connector for two-part vehicle doors comprising a resilient rod having angularly-related parts, and a post on one of said parts said post having a non-circular eye fitting about a non-circular part of the rod whereby oscillation of the post crosswise of the rod may twist the rod, substantially as set forth.
- In witness whereof, I have hereunto set my hand at Connersville, Indiana this 25th day of March, A. D. nineteen hundred and twenty-four.

ROBERT W. HULL.
